(57) CLAIM

The ornamental design for a deck of religious playing cards, as shown and described.

DESCRIPTION

FIG. 1 is a front elevational view of the deck of religious playing cards of the present invention;

FIG. 2 is a rear elevational view of suit 1 of the deck of religious playing cards of FIG. 1;

FIG. 3 is a rear elevational view of suit 2 of the deck of religious playing cards of FIG. 1;

FIG. 4 is a rear elevational view of suit 3 the deck of religious playing cards of FIG. 1;

FIG. 5 is a rear elevational view of suit 4 the deck of religious playing cards of FIG. 1; and,

FIG. 6 is a rear elevational view of preface card and jokers of the deck of religious playing cards of FIG. 1.

The top, bottom and side views of the cards are plain and unornamental and form no part of the claimed design.
